(57) **CLAIM**

I claim the ornamental design for a display screen with animated graphical user interface, as shown and described.

DESCRIPTION

FIG. 1 is a front view of a first image for a display screen with an animated graphical user interface;

FIG. 2 is a front view of a second frame thereof;

FIG. 3 is a front view of a third frame thereof;

FIG. 4 is a front view of a fourth frame thereof;

FIG. 5 is a front view of a fifth frame thereof;

FIG. 6 is a front view of a sixth frame thereof;

FIG. 7 is a front view of a seventh frame thereof;

FIG. 8 is a front view of an eighth frame thereof;

FIG. 9 is a front view of a ninth frame thereof;

FIG. 10 is a front view of a tenth frame thereof;

FIG. 11 is a front view of an eleventh frame thereof;

FIG. 12 is a front view of a twelfth frame thereof;

FIG. 13 is a front view of a thirteenth frame thereof; and,

FIG. 14 is a front view of a fourteenth frame thereof.

The broken line showing of a display screen with graphical user interface is included for the purpose of showing portions of the article which form no part of the claim.

The appearance of the transitional image sequentially transitions between the images shown in FIGS. 1-14. The process or period in which one image transitions to another image forms no part of the claimed design.
